Victor J. Evans
ATTORNEY

UNITED STATES PATENT OFFICE.

JESSIE B. FIELD, OF WAUKESHA, WISCONSIN.

BRUSH.

Application filed October 13, 1926. Serial No. 141,386.

This invention relates to certain novel improvements in pocket brushes and more particularly to a pocket tooth brush and has for its principal object the provision of an improved construction which will be highly efficient in use and economical in manufacture.

A further object of the invention is to provide an article of this character which includes as a part of its structure a holder for supporting a brush head in such a manner that said brush head may be expeditiously removed when it becomes worn or otherwise deteriorated beyond use.

15 A further object of this invention is to provide an article of this character which will be compact thus facilitating placing the article in the vest pocket or the like.

Other objects will appear hereinafter.

20 The invention consists in the novel combination and arrangement of parts to be hereinafter described and claimed.

The invention will be best understood by reference to the accompanying drawing and 25 in which:

30 Fig. 1 is a typical side elevational view of the invention illustrating portions thereof broken away and showing the tooth brush in closed position with respect to the holder,

35 Fig. 2 is a typical side elevational view of the invention showing parts thereof broken away and illustrating the tooth brush in position for use,

Fig. 3 is a slightly enlarged fragmentary 35 sectional detail view taken substantially on line 3—3 of Fig. 2,

Fig. 4 is a sectional detail view taken substantially on line 4—4 of Fig. 2,

40 Fig. 5 is a sectional detail view taken substantially on line 5—5 of Fig. 3,

Fig. 6 is a typical side elevational view of the brush holder embodied in the invention.

45 As herein indicated it is an object of this invention to provide in addition to a tooth brush which will be compact so as to facilitate placing the brush in the vest pocket, a holder for the brush head from which said brush head may be expeditiously removed.

50 It is a known fact that each individual has his preferred selection of a particular shaped brush head and it can be manifestly understood that expense would be involved to provide a pocket holder for each and every

shape tooth brush. It is therefore one of 55 the present objects of this invention to provide a holder for this purpose which will permit the association therewith of any particular style or shaped brush head having the usual shank and whereby the arrangement will be such as will permit the user or retailer of the pocket brush to substitute one shape brush head for an entirely different shape without changing the structure or modifying the pocket holder. 65

To accomplish the various objects of the invention I provide a casing 10 which is formed of any suitable material highly finished or decorated or otherwise ornamented to increase the aesthetic appearance thereof. 70 In the present instance the casing 10, which is elongated in shape, is octagonal in cross section and provided with an interior 11 which is substantially circular in cross section. The end 12 of the casing is provided 75 with a plurality of equally spaced apart vent holes 13 which permit the admission or exit of the air from within the container. The container also is provided in its wall 14 with a vent hole 15 which permits, with the co- 80 operation of the holes 13, proper circulation through the casing. The open end portion 16 of the casing is threaded interiorly as at 17.

The brush holder 18 which also serves as 85 a closure cap for the casing is provided with oppositely disposed reduced end portions 19 and 20 with an intermediate raised portion 21 which is knurled to provide a gripping surface. The portion 20 is threaded and is adapted for threaded engagement with the interior threads 17. The portion 19 has a smooth finished surface and is adapted, when the brush head is in position for use, to be frictionally received in 90 the open end portion 16 of the casing. The holder 18 has formed therein a recess 22 which opens at the end 23 of the portion 19 and opening into this recess is an opening 24 of a diameter smaller than the diameter of 100 the recess 22. Formed in the walls 25 of the holder providing the recess 22 are oppositely arranged parallel extending grooves 26.

The brush head which may be of any approved style and shape, is indicated at 27 and includes a shank 28. This shank 28 is adapted to project through the opening 24

and has formed in its end portion 29 a transverse opening 30 which removably receives a pin 31.

When the brush head 27 is not in use it is confined in the casing 10 and is positioned therein and held against removal therefrom by the holder 18 which has a threaded end portion 20 threaded into the open end portion of the casing. Any moisture which may remain in the bristle of the brush will evaporate by reason of the air circulation in the casing and this will provide a dry, sanitary casing which will not be detrimental to the bristles of the brush. To arrange the brush 27 for use it is only necessary to unscrew the holder 18 from threaded engagement with the casing and after this has been accomplished insert the end portion 19 into the opening end portion of the casing. By reason of the frictional engagement between this end portion 19 and the adjacent interior walls of the casing the brush 27 will be effectively held in position for use.

To associate the brush head with the holder the shank 21 is projected through the opening 24 to dispose the transverse opening 30 thereof beyond the end 23 of the reduced portion 19. This will dispose the opening 30 in position to expeditiously insert the pin 31 therein, it being pointed out that the pin is of such diameter as to frictionally fit in the opening 30. When the pin 31 has been properly inserted through the opening 30 the shank of the brush head is drawn outwardly through the opening sufficient to dispose the pin 31 in its extreme position within the recess 32 with the end portion 32' of the pin engaged in the grooves 26. It is pointed out that the end portion 32' of the pin will frictionally engage the walls of the grooves and thus prevent retroactive movement of the shank of the tooth brush. By the provision of the grooves and the end portions of the pin engaging the grooves it will be manifest that the tooth brush will be prevented from rotating within the holder.

To remove the brush head when the same becomes worn or otherwise deteriorated beyond use or when it is required to substitute a different shape brush head than that shown in the drawing it is only necessary to move the brush head 27 and holder 18 relative to each other to dispose the pin 31 beyond the end of the reduced portion 19 in a position where the pin can be expeditiously removed from the shank of the brush head 27. After the pin has been removed it will be manifest that the brush head 27 can be detached from the holder.

In this construction it will be seen that the ordinary tooth brush may be used and all that is necessary to associate the ordinary

brush with the holder 10' is to thread the end portion of the shank of the brush head 27.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

The invention having been set forth, what I claim as new and desire to secure by Letters Patent is:

1. An article of the class described including a brush head, a casing adapted to house the brush head when said brush head is not operative and having an open end portion, a plug having one end portion threaded for threaded engagement with the open end portion of the casing and having an opposite end portion provided with a smooth cylindrical surface adapted for frictional engagement in the open end of the casing and provided with a recess and an opening opening into the recess and having wall portions provided with oppositely disposed parallel extending grooves, said brush head including a shank adapted to project through the opening and having a transverse opening formed therein, and a pin positioned in the transverse opening and having opposite end portions frictionally engaged in the grooves. 90

2. An article of the class described including a brush head, a casing adapted to house the brush head when said brush head is not operative and having an open end portion, a plug having one end portion threaded for threaded engagement with the open end portion of the casing and having an opposite end portion provided with a smooth cylindrical surface adapted for frictional engagement in the open end of the casing and provided with a recess and an opening opening into the recess and having wall portions provided with oppositely disposed parallel extending grooves, said brush head including a shank adapted to project through the opening and having a transverse opening formed therein, and a removable pin positioned in the transverse opening and having opposite end portions frictionally engaged in the grooves, said pin being normally concealed in said recess when said holder and said brush head are in operative position with respect to each other and adapted to be moved from concealed position in the recess upon relative movement between the holder and the brush head 120 in a certain direction. 110

In testimony whereof I affix my signature,
JESSIE B. FIELD,
